UNITED STATES PATENT OFFICE

2,609,753

FUSE FUNCTIONING MECHANISM

Herbert L. Rosenberg, Aberdeen, Md.

Application March 23, 1949, Serial No. 83,056

3 Claims. (Cl. 102—76)

(Granted under the act of March 3, 1883, as amended April 30, 1928; 370 O. G. 757)

1

The invention described herein may be manufactured and used by or for the Government for governmental purposes without the payment of any royalty thereon.

This invention relates to improvements in fuses of the type which have a small delay in functioning after impact with a target thereby permitting the continued travel of a projectile armed with one of the improved fuses a desired distance before being subjected to the action thereof.

One of the principal objects of the invention is the provision of an impact fuse which is especially adapted to effect the optimum performance of explosive projectiles used against aircraft and other targets of a similar character.

Another important object of this invention is the provision of a fuse which will utilize centrifugal action after impact as the force for actuating the fuse whereby the time of fuse functioning may be controlled after impact in accordance with mathematical deductions derived from the laws governing centrifugal force.

With the foregoing and such other objects in view as will hereinafter more fully appear, the invention resides in the novel arrangement and combination of parts and in the details of construction set forth in the following description and defined in the appended claims.

In the drawings accompanying this specification and forming a part thereof.

Figure 1 is a longitudinal sectional view of one form of fuse constructed in accordance with the present invention;

Figure 2 is a longitudinal sectional view of a modification of the fuse shown in Figure 1;

Figure 3 is a cross sectional view taken upon the line 3—3 of Figure 2;

Figure 4 is a longitudinal sectional view of another form of fuse constructed in accordance with the present invention;

Figure 5 is a cross sectional view taken upon line 5—5 of Figure 4; and

Figure 6 is a cross sectional view taken upon the line 6—6 of Figure 4;

Figure 7 is a cross sectional view taken upon the line 7—7 of Figure 1;

Figure 8 is a longitudinal cross sectional view taken upon the line 8—8 of Figure 1.

The several forms of fuse constructions shown in the drawings are intended for use with rotated projectiles and are each so constructed as to function, after action is initiated through impact, with a target, in a manner that will introduce a desired delay in the fuse action after impact. The delay referred to is designed to accomplish fuse

2

action when the projectile occupies a position relative to the target to be most effective when detonated and is predetermined in accordance with the following factors deduced as shown by way of one example.

Assume:

- (a) A fused projectile to have a striking velocity of 2,000 ft./sec;
- 10 (b) That the projectile of (a) has a rotational striking speed of 35,000 R. P. M.;
- (c) That optimum effectiveness of the projectile will be obtained when it has traveled a distance of 9" after impact with the target;
- 15 (d) That unknown variables such as decreases in linear and angular velocities can be disregarded during the projectile's penetration of the target because of the characters of the target.

20 Based upon the assumptions of (a), (c) and (d) it follows that the distance of 9" of (c) will be traversed by the projectile in time $t=3/8000$ sec.

It is well known that:

25
$$1. F = M \frac{V^2}{r}$$

Where:

 F =centrifugal force in lbs. M =mass r =distance (c. g. of rotors Figs 1 and 2 or of firing pin Fig. 4 and axis of shell rotation) V =linear velocity along orbit of rotation N =R. P. M. R =the general expression of r or radius of orbit of rotation

35 but

$$2. V = \frac{\pi NR}{30}$$

So by substituting in (1)

$$30 3. F = \frac{M \pi^2 N^2 r}{900}$$

$$= \frac{(3.14)^2 (35,000)^2 M r}{900}$$

$$= 13.60 \times 10^6 M r$$

If the rotors of Figures 1 and 2 or the firing pin of Figure 4 are free to move, the acceleration of the c. g. thereof perpendicular to the axis of the shell is:

40 4.
$$a = \frac{F}{M}$$

Where

 a =acceleration perpendicular to the axis of the shell

Substituting F from (3) in (4)

$$5. \quad a = \frac{13.60 \times 10^6 Mr}{M}$$

$$6. \quad = 13.60 \times 10^6 r$$

As acceleration is a direct function of the radius of the orbit of rotation, average acceleration over a distance "S" can be taken as the average between initial radius of c. g. " r_1 " and final radius of c. g. " r_2 ". Then from (6)

$$7. \quad a_{av.} = 13.60 \times 10^6 \times \frac{r_1 + r_2}{2}$$

but

$$8. \quad S = \frac{1}{2} a_{av.} t^2$$

Substituting $a_{av.}$ of (7) and t of above assumptions in (8)

$$9. \quad S = \frac{1}{2} \times 13.6 \times 10^6 \times \frac{r_1 + r_2}{2} \times \left(\frac{3}{8000} \right)^2$$

but S the distance the rotors of Figures 1 and 2 or firing of Figure 4 move to effect detonation of the detonator is $r_2 - r_1$

$$10. \quad r_2 - r_1 = \frac{13.60 \times 10^6 \times 3^2 \times (r_1 + r_2)}{2 \times 2 \times (8000)^2} \\ = .478r_1 + .478r_2$$

$$11. \quad r_2 = \frac{1.478}{.522} r_1 = 2.83r_1$$

If F_2 is the force of impingement of the firing pin and detonator then from (3)

$$12. \quad F_2 = 13.60 \times 10^6 Mr_2$$

As the relative striking velocity V_s of the firing pin and detonator is

$$13. \quad V_s = a_{av.} t$$

then from (7)

$$14. \quad V_s = \frac{13.60 \times 10^6 (r_1 + r_2)}{2} \times \frac{3}{8000}$$

$$15. \quad = 2.55 \times 10^3 (r_1 + r_2)$$

From the above it will be noted that the factors affecting fuse functioning and delay may be utilized to control the essential fuse components to act in accordance with predetermined desirable results.

Referring now more particularly to the drawings and specifically to the form of fuse disclosed in Figure 1 there is shown a die cast or otherwise formed fuse body 10 of any suitable material. The body 10 may be formed for attachment to the nose of a projectile as by the external threads 11 arranged adjacent the base thereof as shown and may be internally threaded as indicated at 12 for engaging complementary threads on a booster cup 14 for retaining the booster cup in the booster well of fuse body 10. The booster cup is conventionally charged with a charge 15 of tetryl or similar explosive.

A rotor assembly generally designated 16 is positioned within an internal cavity of the fuse body 10 intermediate the booster and nose portion of the fuse and comprises a rotor housing 17, which may be a die cast aluminum-base alloy or any similar material, and a sleeve 18 of brass or the like affixed to and enclosing the housing 17 is snugly fitted into the fuse body cavity as shown. The housing 17 is a generally cylindrical block provided with a diametral slot 19 designed to receive a truncated disc shaped rotor element 20 pivoted on either side by pivot pins 21 journalled in suitably aligned journal wells 22 formed in the side walls defining slot 19. Rotor element 20 is formed with a bore adjacent to and parallel with the plane of truncation

thereof for housing a detonator assembly 23 charged with any desirable priming mixture. The rotor element may be rotated upon its pins 21 so as to bring the detonator assembly 23 into line with a booster lead 24 centrally located in the bottom of housing 17 thus establishing the usual explosive train through the fuse.

A firing pin 25 affixed within the fuse as shown is adapted to be impinged by the detonator assembly 23 through the opening 26 in rotor element 20 as the rotor element swings about its pivots 21 to bring the detonator assembly into line with booster lead 24.

The nose portion of the fuse body is formed with an axial bore 27 communicating with the interior cavity of the fuse body within which a plunger 28 and rotor release block 29 are slidably positioned in interconnected relation by pivot bar 30 and levers 31 as shown whereby inward axial movement of plunger 28 will effect outward axial movement of rotor release block 29. In the unarmed condition of the fuse the plunger 28, rotor release block 29 and rotor element 20 occupy the relative positions shown in Figure 1. Although the linkage for effecting conjoint opposed movement of the plunger 28 and rotor release block 29 is shown as being comprised of the pivot bar 30 and levers 31 it will be understood that any suitable linkage adapted to accomplish this purpose may be used. If desired the rotor element may be additionally locked in the unarmed position shown in Figure 1 by pins 32 adapted to be moved into unlocking position under the action of centrifugal force against the spring 33 in a conventional manner.

In operation the rotor release block 29 will be designed to have more mass than the plunger 28 and will therefore remain in the position shown in Figure 1 under the action of the force of setback during passage of the fuse on a projectile through the bore of a gun in firing. If the fuse is provided with the locking pins 32 these pins will disengage the rotor element 20 under the action of centrifugal force during the passage of the fuse through the bore as is well understood. During flight of the projectile the creep force acting on the rotor release block 29 will be overcome by the fractional resistance movement thereof under this force through the engagement of the rotor element 20 therewith under the action of centrifugal force. Upon impact with a target the plunger 28 is driven axially inward removing the rotor release block 29 through linkage 31-30-31 from the path of movement of rotor element 20. Under the force of centrifugal action the rotor element 20 rotates on pins 21 impinging the detonator 23 upon firing pin 25 when the detonation train 23, 24 and 15 are in alignment. The desired time delay will depend upon the time required for the detonation train to become aligned which may be controlled by the formulae above derived. A delay sufficient to give a 9 inch penetration in the type of target referred to may for example be obtained under the assumptions used in deriving the formulae by adjusting r_2 to equal 2.83 times r_1 in this fuse where r_2 is the distance between the axis of rotation and firing position of the center of gravity of rotor element 20 and r_1 is the distance between the axis of rotation and unarmed position of the center of gravity of the rotor element 20.

In the modification illustrated by Figure 2 of the drawings there is shown a die cast or otherwise formed fuse body 34 of any suitable material. The body 34 may be formed for attach-

ment to the nose of a projectile as by external threads 35 arranged adjacent the base thereof as shown, and may be internally threaded as indicated at 36 for engaging complementary threads on a booster cup 37 for retaining the booster cup in the booster well of fuse body 35. The booster cup is conventionally charged with a charge 38 of tetryl or similar explosive. A rotor assembly generally designated 39 is positioned within an internal cavity of the fuse body 34 intermediate the booster and nose portion of the fuse and comprising a rotor housing 40 which may be a die cast aluminum base alloy or similar material, a sleeve 41 of brass or the like affixed to and enclosing the housing 40 is snugly fitted into the fuse body cavity as shown. The housing 40 is a generally cylindrical block provided with a diametrical slot 42 designed to receive a disc shaped rotor element 43 pivoted on either side by pivot pins 44 journalled in suitably aligned journalled wells 45 formed in the side walls defining slot 42. The rotor element 43 is formed with a bore for housing a detonator assembly 46 charged with any desirable primary mixture. The rotor element may be rotated upon its pins 44 so as to bring the detonator assembly 46 into line with a booster head 46a centrally located in the bottom of housing 39 thus establishing the usual explosive train through the fuse. The nose of the fuse body is formed with an axial bore 47 having a plunger 48 slidably housed therein. The plunger 48 comprises a narrow stem portion 49 slidably in a reduced section of the bore 47 having one end as at 50 slidably fixed in the enlarged portion of the axial bore 47. The opposite end of the stem 49 is provided with an enlargement 51 slidably fitted in the bore 52 of a keyhole slider 53 which is slidably mounted in a transverse slot 54 communicating with the internal cavity of the fuse body 34 and the axial bore 47. The downward movement of plunger 48 is prevented by the rotor 43 until the recess 58 of the detonator assembly is aligned with the plunger 48. The keyhole slider 53 is provided with an enlarged opening 55 communicating with the bore 52. At one end of the keyhole slider is fastened an L-shaped firing pin 60 projecting downwardly into the slot 42a and inwardly toward the detonator so that when the fuse is in armed position said firing pin will be in alignment with the opening 59 in the rotor 43. The rotor element is locked in the unarmed position by the pins 56 adapted to be moved into unlocking position under the action of centrifugal force against the spring 57 in a conventional manner.

In operation the enlargement 51 of the plunger 48 upon set back in the gun will engage a matching section 61 in the rotor and prevent movement of the rotor until the projectile leaves the muzzle of the gun. The rotor centrifugal lock pins 56 now move outward and the rotor 43 then swings into armed position, bringing the opening 59 of the detonator 46 into alignment with the firing pin and the recess 58 into alignment with the enlargement 51 of the plunger 48.

Upon impact the plunger 48 is driven downward causing the enlargement 51 to enter the recess 58 and the stem 49 of the plunger to be positioned in the bore 52 of the keyhole slider 53. The keyhole slider is now free to move under the impetus of centrifugal force and the firing pin 60 carried by the keyhole slider is driven into the detonator through the opening 59. The desired time of delay will be determined by the time of firing pin travel which can be calculated in accordance with the formulas derived above.

Figure 4 of the drawing illustrates another fuse employing the principles of this invention in which there is shown a fuse body 61' threadedly engaged to an axially bored nose portion 62. The base of said body may be internally threaded as at 63 for engaging complementary threads on a booster cup 64 for retaining the booster cup in the booster well of the fuse body 61'. The booster cup contains a conventional charge 65 of tetryl or similar explosive. A transverse slot is formed in the top portion of the body 61' as at 66 in which is slidably fitted a keyholed slider 67 having a firing pin 68 affixed to one end opposite a detonator 69 projecting from said body and in communication with said booster. A plunger 70 in the axial bore 71 of the nose portion has a thin section 72 and an enlarged end portion 72a normally positioned and retained in the bore 73 of the keyholed slider by a pair of centrifugal pins 74 in a transverse slot 75 in the body 61' immediately below and in communication with the transverse slot 66. The centrifugal pins being held centrally of said body by a frangible pin 76. In operation the set back of the plunger 70 will prevent movement of the centrifugal pins 74. As the projectile leaves the muzzle of the gun the pins 74 move outwardly.

Prior to impact with the target the plunger 70 is prevented from entering the transverse slot 75 by a combination of creep force and friction between the keyholed slider and the enlarged end portion 72a. On impact with the target the plunger is driven down so that its thin section 72 passes through the keyholed slider. The slider with its firing pin 68 is now free to move under the impetus of centrifugal force to puncture the detonator 69, starting the detonation wave that travels through the explosive train. The time of delay depends on the desired time of firing pin movement calculated in accordance with the above formulas.

I claim:

1. In a time delay fuse for projectiles comprising a hollow body having an axial bore in the nose thereof, booster means in the opposite end of said body, firing means in said body, rotor means including detonator means positioned in operable relationship to said firing means in said hollow body intermediate said nose and said opposite end, said rotor means having its center of gravity initially spaced from the axis of rotation, releasable locking means positioned within said bore comprising a pivoted bar supporting a forwardly directed lever on one end and a rearwardly directed lever on the other end, each of said levers supporting a mass normally in alignment with said axial bore, the mass supported by said rearwardly directed lever normally extending into the path of travel of said rotor and restraining the same against movement caused by centrifugal force prior to impact, said levers moving in opposite directions upon impact to release said rotor to the action of centrifugal force, said time delay being determined by the time required for the center of gravity of said rotor to travel a distance equal to a constant times the initial distance of said center of gravity relative to the axis of rotation.

2. A time delay fuse for a projectile comprising a hollow body having an axial bore in the nose thereof, a booster positioned in the base of said body, a cavity formed intermediate said axial bore and said booster, a firing pin fixed in the walls of said cavity, a detonator carried by a rotor pivotally supported within said cavity

in operable relationship to said firing pin, the center of gravity of said rotor being initially spaced from the axis of rotation, said pivoted rotor having locking means released by centrifugal force and rotated toward said firing pin under the influence of said centrifugal force, said axial bore having a plunger positioned therein and pivotally connected to a rotor release block of greater mass than said plunger, said rotor release block engaging said pivoted rotor upon set back and restraining it against action of centrifugal force prior to impact, the time of delay after impact being determined by the time required for the center of gravity of said rotor to travel a distance equal to a constant times the initial distance of said center of gravity relative to said axis of rotation.

3. A time delay fuse for a projectile comprising a hollow body having an axial bore in the nose thereof, booster means positioned in the base of said body, rotor means carrying a detonator and pivotally supported in a cavity intermediate said axial bore and said base, the center of gravity of said rotor means being initially spaced from the axis of rotation, a firing pin 20 transversely positioned in said cavity in operable relationship to said rotor means; said axial bore having a plunger positioned therein and pivotally connected to a rotor release block of

5
10
15

greater mass than said plunger, said rotor release block reacting to the force of set back to restrain said rotor against the action of centrifugal force prior to impact, said release block holding said rotor in spaced relationship to said firing pin, said plunger upon impact withdrawing said release block to free said rotor to the action of centrifugal force to impinge said detonator upon said firing pin, the time of delay after impact being determined by the time required for the center of gravity of said rotor to travel a distance equal to a constant times the initial distance of said center of gravity relative to said axis of rotation.
